CIRCUIT CONTROLLER

Clifford C. Bradbury, Glencoe, Ill., assignor to
 Bendix Home Appliances, Inc., Detroit, Mich.,
 a corporation of Delaware

Application May 6, 1937, Serial No. 141,081

9 Claims. (Cl. 74—125)

The present invention relates to circuit controllers and particularly to rotary circuit controllers of the type driven in a predetermined direction in periodic steps through a pawl and ratchet mechanism actuated by a constant speed motor.

In a circuit controller of the above type, such for instance as that forming the subject matter of the copending application of Rex E. Bassett, 10 Jr., Serial No. 240,163, filed November 12, 1938 (Case 10), a constant speed motor is utilized to drive a single step cam at constant speed. The cam in turn imparts oscillatory motion to a pivotally mounted pawl carrying arm that is 15 forced to follow the cam by a relatively heavy spring. A pawl provided with a toothed portion adapted to engage a ratchet wheel is pivotally mounted upon the arm and adapted to impart movement to the ratchet wheel as it is reciprocated by the oscillation of the arm. The pawl is held in engagement with the ratchet wheel by the spring, mentioned above, which is preferably secured to the pawl and to a pivotally mounted dog adapted to prevent retrograde motion of 20 the wheel. The ratchet wheel is secured to and drives a shaft upon which is mounted a series of cams adapted to actuate resilient contact carrying members biased to circuit closing position.

A controller of the above type permits the use 25 of relatively inexpensive resilient contact carrying members for the reason that the disengagement of the contacts is made to depend not upon the resiliency of the contact carrying members themselves, but upon the rapidity of movement 30 of the cams.

The rapidity of movement of the cams is dependent upon the strength of the spring biasing the pivotally mounted pawl carrying arm toward the motor driven cam. It is, therefore, desirable 35 to make the spring strong in order to effect rapid disengagement of the contacts. However, it has been found that if the spring is made too strong the ratchet wheel is given a sudden impulse which carries it more than the unit distance it is designed to be moved by the cam actuated pawl and ratchet mechanism. In other words, if the spring is too strong it causes "overrunning."

Circuit controllers of the type forming the subject matter of the above mentioned Bassett application, were designed particularly for use with 40 washing machines. While these machines normally can be operated according to a predetermined cycle of operations for which the controller is designed, it sometimes happens that 45 it is desirable either to hasten or omit the per-

formance of certain functions. For this reason the controllers are provided with means permitting manual operation of the cams, whereby certain operations may be hastened or omitted entirely.

The primary object of the present invention is to provide a new and improved controller of the type described above in which the possibility of "overrunning" is eliminated.

A further object of the present invention is to provide a controller of the above type with means adapted positively to prevent "overrunning" of the ratchet wheel and controller when the latter is actuated through the pawl and ratchet mechanism, thereby permitting the use of springs 50 sufficiently strong to enable the controller to be moved with desired rapidity.

A further object of the present invention is to provide a controller with means adapted positively to prevent "overrunning" of the controller, but so designed that the controller may be manually rotated whereby the performance of functions by the machine controlled thereby may be selected, hastened or omitted, as desired.

Further objects and advantages of the invention will become apparent from the ensuing description in which reference is had to the accompanying drawings illustrating embodiments thereof.

In the drawings:

Fig. 1 is a fragmentary vertical section of a cabinet showing one form of a circuit controller, constructed in accordance with the present invention, mounted therein;

Fig. 2 is a side elevation of the circuit controller of Fig. 1, with the housing and parts thereof shown in section;

Fig. 3 is a fragmentary longitudinal section taken through the pawl and ratchet mechanism and the circuit controlling portion of the controller;

Fig. 4 is a perspective view showing the details of a prong contact and movable contact carrying member of the circuit controller;

Fig. 5 is a front elevation, partially in section, of the multiple section switch actuating cam;

Fig. 6 is a rear elevation, partially in section, of the switch members;

Fig. 7 is a transverse vertical section taken along the line 7—7 of Fig. 2, and showing the pawl and ratchet mechanism and the means for preventing "overrunning" of the controller;

Fig. 8 is a fragmentary top plan view of the details shown in Fig. 7;

Fig. 9 is a view similar to that shown in Fig. 7 of a modified form of means for preventing "overrunning"; and

Fig. 10 is a view similar to Fig. 8 of the modification shown in Fig. 9.

The circuit controller embodying the present invention and illustrated in Figs. 1 to 8, inclusive, comprises a fixed multiple socket receptacle secured in suitable fashion to the washing machine, or the like, and a unitary removable casing provided with prong contacts adapted to be inserted into the sockets. The sockets are connected in circuit with a source of energy and to the various devices that are to be controlled by the circuit controllers.

The unitary removable casing carries not only the circuit controller and the actuating means therefor, but also a manually operable knob which indicates the position of the controller and by means of which the operation of the apparatus may be hastened or selected, as herein-after described.

Referring first to Fig. 1, the controller, indicated generally by reference numeral 11, is shown installed in position on a side wall 12 of a washing machine cabinet. In this position the unitary removable casing 13 of the controller is shown adjacent the fixed receptacle 14 where it is supported not only by the prong contacts (see Fig. 2), but by a horizontally disposed bracket 15 to which it is secured by a surrounding steel strap 16. The controller is provided with an indicating and adjusting knob 17 cooperatively associated with a dial plate (not shown) comprising suitable indicia for indicating the various functions that are performed by the washing machine.

From Fig. 2 it may be noted that the casing 13 is formed substantially in the shape of an elongated cup, the front end of which is closed by a substantially circular combined closure and support 21 made of suitable insulating material. The closed rear end 22 of the casing 13 is provided with a flanged opening 23 through which extends a pair of conductors 24 leading to a constant speed motor, indicated generally by reference numeral 25, mounted within the casing.

The motor 25 is supported in the rear end of the casing by the end portion 22 of the latter and a metallic support 26 secured within the casing approximately halfway between the end 22 and the insulating front support 21 by the screw bolts 27 and spacing blocks 27A. The intermediate support 26 is separated from the casing by a relatively thin insulating sheet 28.

The motor may be of any well known type of construction and comprises a laminated field core 29, a portion of which supports a field coil 30. The field core is supported upon a pair of external bosses 31 only one of which is shown, formed integrally with a gear casing 32 supported in turn upon the intermediate support 26 by a plurality of screw bolts 33. The casing 32 is spaced from the intermediate support by a plurality of spacing blocks 34 surrounding the bolts. The field core 29 is secured to the vertical bosses 31 by double-ended nuts 35, the other ends of which receive screw bolts 36 passing through suitable apertures in the rear portion 22 of the casing 13.

The motor 25 is preferably of the shaded pole self-starting type provided with shading coils 37 encircling portions of the laminated field core 29 between which is mounted an armature (not shown) of usual type. The armature is mechan-

ically connected through gears in casing 32 to a shaft 38 (see Fig. 3) extending through an external boss 39 formed at the front side of the gear casing and to the end of which is mounted a single step cam 41.

The cam 41 is rotated at a reduced speed by the motor and is adapted to drive through a pawl and ratchet mechanism, to be described fully hereinafter, a cam shaft 45 journaled for rotation in a brass bearing bushing 46 mounted centrally of the intermediate support 26 and a combined spacer and bearing bushing 47, a reduced portion 48 of which is mounted in the front insulating support 21.

The method of mounting the cam shaft, as well as the cam and switch structure about to be described, form no part of the present invention, but are disclosed and claimed in the previously mentioned copending application of Rex Earl Bassett, Jr.

A multiple section cam 51 comprising a guiding portion 52 and four cam surfaces or sections 51A to 51D, inclusive, the diameters of which increase with the distance of the particular cam section from the support 21, is mounted for rotation with the cam shaft 45. The cam is fixedly secured to a hub 53 by means of an annular shoulder 54 provided at the front end of the hub, seating in a recess 55 formed in the front end of the cam, and a rolled-over portion 56 securing in place an annular washer 57, also mounted in a recess formed on the rear side of the cam 51. The hub is secured to the cam shaft 45 near the intermediate support 26 by suitable means, such as the knurling 58. The cam is separated from the front combined spacer and bearing bushing 47 by an intermediate insulating spacer 59.

The cam sections 51A to 51D have associated therewith resilient generally longitudinally extending contact carrying switch blades 61A to 61D, inclusive. These blades are provided with cam engaging rear portions 62 and transversely extending perforated portions 63 through which prong contacts 64 extend. The prong contacts are provided with shoulders 65 adapted to abut against the front side of the support 21 and are peened over as indicated at 66, whereby the contact forms the sole support for the contact carrying blade. The blade is provided with a longitudinal flange 67 adapted to enter a recess in the support whereby the blade is secured against movement on the support.

The various prong contacts associated with the switch blades 61A to 61D, inclusive, have been indicated by the reference numerals 64A to 64D, inclusive, and the construction of the combined prong contact and switch blade may be noted best from Figs. 3 and 4.

The resilient switch blades carry contacts 68A to 68D, inclusive. The latter are adapted to be selectively moved into and out of engagement with fixed contacts 69A to 69D, inclusive, located radially inward from the first mentioned contacts and mounted upon a substantially rigid support 71. The support 71, as may be seen from Fig. 6, substantially surrounds the cam shaft 45 and it is secured to the front support 21 by means of a prong contact 72 and a rivet 73.

The prong contacts 64A to 64D, inclusive, and 72 are adapted to be inserted into similarly located sockets 74A to 74D, inclusive, and 75 mounted in a support 76 forming a closure for the rear end of the fixed receptacle 14 to which it is secured by a bent-over tongue portion 77. The support 76 is made of three strips 81, 82 75

and 83 of insulating material provided with apertures coaxially located with respect to the various contact prongs. The sockets 74A to 74D, inclusive, and 75 are formed with flanged portions 84 adapted to seat in recesses 85 formed in the middle strip 82 and are provided with tongue-like terminals 86 adapted to extend through recesses 87 formed in the front strip 82 whereby, when the strips are assembled in the position shown, particularly in Fig. 3, the sockets are securely held in place.

The contact terminals 86 may be connected to a suitable source of energy and the various control devices associated with the apparatus to be controlled. If the controller is to be used with a washing machine, the connections may be made after the disclosure in the copending applications of Rex Earl Bassett, Jr., filed February 14, 1935, Serial No. 6,425, Aaron A. Loweke, filed May 8, 1936, Serial No. 78,692, or Rex Earl Bassett, Jr., and John W. Chamberlin, Serial No. 129,429, filed March 6, 1937, the last mentioned of which contains a complete discussion of a washing cycle of the type for which the present controller is specifically designed. According to these disclosures the fixed contacts 68A to 69D, inclusive, are connected to one terminal of the source of energy. The movable contacts associated therewith are connected through prong contacts and sockets, with one terminal of the various control devices, the other terminals of which are connected to the other terminal of the source of energy. Thus each time the contacts 68 and 69 are in engagement, the control device is energized. In practice the cam 51A controls the motor 25, and from Fig. 6 it may be seen that the contacts 68A and 69A are closed except for a brief interval, which corresponds to the "off" position of the apparatus and from which it is necessary manually to move the controller through the indicating knob 17. Once moved from the "off" position, the motor 25 is energized and rotates the cams through one complete revolution, corresponding to the cycle of operation of the machine.

The indicating knob 17 is secured to the front reduced end 88 of cam shaft 45 which extends outside the receptacle 14 and cabinet wall 12. It may be secured to the shaft by suitable means, such as the set screw 89.

A spacing and insulating bushing 91 surrounds that portion of cam shaft 45 within the fixed receptacle 14. The bushing 91 is secured against longitudinal of displacement along the shaft by a collar 92 seated in a groove 93 thereof. The various electrical conductors (not shown) lead to the terminals 86 through a flanged opening 94 provided on the lower side of the fixed receptacle 14, as shown in Fig. 2.

In the description of the means for imparting periodical rotary motion to the cam shaft and the means for preventing "over-running" thereof reference will be had in particular to Figs. 2, 3, 7 and 8.

The movement imparting means comprises a pawl and ratchet mechanism adapted to be actuated by means of the cam 41 which is, as heretofore described, driven at a constant speed by the electric motor 25. The cam is adapted to impart oscillating motion to a pawl carrying arm 97 pivotally mounted upon a stud 98 secured in suitable manner to the intermediate support 26.

From Figs. 2, 7 and 8 it may be noted that the

pawl carrying arm 97 is on the opposite side of support 26 from the cam 41, but is provided with a transverse projection 99 located substantially halfway between the opposite ends thereof and extending into the path of movement of the cam 41 through an aperture 101 provided in the intermediate support. The tendency of the pawl carrying arm to bind is avoided by providing the arm with a second projection 102 extending toward the cam and adapted to ride on the guiding portion 52 thereof.

A pawl 103 is pivotally mounted upon a pin 104 fixedly secured to the free end of the arm 97 and is guided in its movement by a pair of washers 105 mounted on opposite sides thereof on the pin 104. The pawl 103 is approximately one-half the length of the pawl carrying arm 97 and extends tangentially toward a ratchet wheel 106 fixedly mounted on cam shaft 45 and is provided with a tooth engaging portion 107 adapted to engage the teeth of the ratchet wheel.

The tooth engaging portion 107 is tapered in form and is provided with a flat upper portion 108 disposed at an angle of approximately 45° adapted to engage a similarly disposed extension 109 of a stop arm 110 pivotally mounted upon a pin 111 fixedly secured to the intermediate support 26. A dog 112 is also pivotally mounted upon the pin 111 and is spaced from the stop arm by a washer 113 and from the intermediate support by a second washer 114.

Referring now particularly to Figs. 7 and 8, it may be noted that the stop arm 110 is provided with an upper broadened and curved surface 115 displaced forward from the plane of the pawl 97 and ratchet wheel. The movement of the stop arm toward the ratchet wheel and the surface 108 of the pawl is prevented by a pin 116 mounted upon the intermediate support 26 between the arm and the ratchet wheel and adapted to abut against the concave lower surface 117 of the arm.

The stop arm as well as the pawl 103 and dog 112 are maintained in resilient engagement with the teeth of the ratchet wheel by means of a helical tension spring 118 secured at its ends to pins 121 and 122 mounted upon the pawl and dog, respectively. These pins are located at a distance farther from the axis of rotation of the ratchet wheel than a line passing through the centers of the pivot points 104 and 111 of the pawl and dog, respectively. The underside of spring 118 engages the top curved surface 115 of the dog, and is thus given a generally V-shaped form because the highest point of the curved surface 115 is beyond a line passing through the pins 121 and 122. The pivot points 98, 104 and 111 of the pawl carrying arm 97, the pawl 103 and dog 112 are substantially equidistant from each other and from the axis of rotation of the ratchet wheel. These pivot points are also at a radial distance from the axis of rotation greater than the radius of the wheel, whereby a single spring such as that illustrated is enabled not only to maintain the pawl and dog in engagement with the ratchet wheel, but also to maintain the pawl carrying arm 97 in cooperative relationship with the constant speed cam 41.

Furthermore, the arrangement is such as will permit of the manual rotation of the cam shaft by the indicating knob whenever it is desired either to hasten or select performance of certain functions by the apparatus controlled by the circuit controller.

When it is desired to place the apparatus in

- operation, the indicating knob 17 is manually turned in a clockwise direction from its "off" position, in which all the circuits controlled by the controller are open, to energize the motor 25. 5
 5 The control is such, as explained above, that once the motor is energized, it remains energized until the controller has completed a single revolution and thereby caused the apparatus to go through a cycle of operations, which in the case of a 10 washing machine includes the steps of washing, rinsing and extracting.

Once the control motor 25 is energized, it drives the cam 41 at a constant speed through the gears housed in casing 32. As the cam rotates, it actuates the pawl carrying arm 97 in a 15 counterclockwise direction, as viewed in Fig. 7, against the bias of the spring 118. The pawl carrying arm is gradually moved to an extreme 20 counterclockwise position and then falls off the high point of the cam 41. The spring 118 immediately and forcibly actuates the arm 97 in a clockwise direction and moves the ratchet wheel a unit distance. If the stop arm 110 were not 25 provided and the spring 118 made heavy enough to provide the desired rapid movement of the cam shaft, the arm 97 might be moved so rapidly that the pawl 103 would give the ratchet wheel a sudden impulse, such that would cause the ratchet wheel and cam shaft to rotate more than 30 a unit distance. This "overrunning" is possible because, when the pawl tooth 107 strikes a particular tooth, it strikes it with considerable force, and if the force were great enough the impulse 35 transmitted to the wheel would cause the ratchet wheel to raise the pawl just as though the cam shaft were rotated manually.

This "overrunning" of the clutch is, however, prevented by the stop arm 110 which wedges the pawl tooth 107 therebetween and the ratchet 40 wheel. When the pawl reaches its limiting position, as indicated in Fig. 7, the surface 108 of the pawl abuts against the flanged portion 109 of the stop arm, thereby wedging the pawl tooth 107 between a ratchet tooth and the stop arm. 45 Thus, even though a relatively heavy impulse is transmitted to the ratchet wheel, the spring 118 acting through the stop arm prevents upward movement of the pawl by the ratchet wheel; consequently "overrunning" of the clutch is prevented. 50

During the normal course of operation of the controller by the motor 25, the cam shaft is actuated in a single direction in periodic steps of unit 55 distance. In some instances it is desirable either to hasten or omit certain functions of the apparatus controlled by the controller and for this reason it is desirable that the controller be so constructed that it can be manually operated. The present controller is constructed in this fashion and whenever it is desired manually to rotate the controller the indicating and adjusting knob 17 is turned in a clockwise direction. The dog 112 permits the ratchet wheel to be rotated in this direction, but not in the opposite direction. 60 When the indicating knob is rotated in a clockwise direction, the pawl tooth is forced upwardly by the ratchet wheel, a tooth of the latter engaging the bottom of the pawl tooth and forcing the latter upward against the bias of the 65 spring 118. The spring 118 should, therefore, be made heavy enough to obtain the desired rapidity of movement of the cam shaft, but not too strong to prevent manual rotation of the controller. 70

75 The modified form of construction illustrated

in Figs. 9 and 10 is substantially the same as that just described, with the exception that the forms of the dog and stop arm have been changed slightly. For this reason it is not believed necessary to give a detailed description of the construction of the entire controller, and thus only the escapement mechanism has been illustrated and is described in detail below. 5

From Figs. 9 and 10 it may be seen that the cam 41 is adapted to impart oscillatory movement to the pawl carrying arm 97 through the projection 99 formed integrally with the latter and extending through an aperture 101 on the intermediate support 26 into cooperative relationship with the cam. The pawl carrying arm 97 is pivotally mounted on the intermediate support upon the pin 98 and has a pawl 103 pivoted thereto at its free end upon a pin 104. The pawl 103 is mounted between a pair of washers 105 also mounted upon the pin 104. 20

A ratchet wheel 106 is adapted to be engaged by the tooth 107 of the pawl so that as the pawl carrying arm is oscillated the pawl is given a reciprocatory motion and rotates the ratchet wheel 106 a unit distance upon each oscillation 25 of the arm.

The pawl 103 is provided with a diagonal upper surface 108 adapted to abut against a pin 131 carried by a stop arm 132 pivotally mounted upon the pin 111 secured to the support 26. The movement of the stop arm 132 toward the ratchet wheel is limited by a pin 116 secured to the support between the lower concave surface 133 of the stop arm and the ratchet wheel. Retrograde motion of the ratchet wheel is prevented by the 35 dog 134 also pivotally mounted upon the pin 111. The pawl 103, the dog 134 and the stop arm 132 are all biased toward the ratchet wheel by a helical tension spring 118 mounted upon pins 121 and 122 secured to the pawl and dog, respectively. 40

The stop arm is provided with a sector shaped forwardly extending projection 135 against the upper side of which the underside of the helical springs abuts, thereby forcing the stop arm downward into engagement with the pin 116. 45

It may be seen from Figs. 9 and 10 that the construction of the escapement mechanism is substantially the same as that described above, and that the pawl carrying arm 97, the pawl 103 50 and the dog 134 are pivotally mounted at points corresponding to those at which the similar elements of the previous modification were mounted. The spring 118 is likewise mounted in like manner to the pins 121 and 122, which are 55 located, with respect to the pawl and dog, in such manner that the latter are biased into engagement with the ratchet wheel.

The operation of the modification just described is substantially the same in all respects 60 as the operation of the modification last described. The cam 41 is rotated at a constant speed by the control motor and imparts oscillatory movement to the pawl carrying arm 97. The latter in turn imparts reciprocating motion 65 to the pawl 103 of an amplitude such as to impart rotation to the ratchet wheel 106 in steps of a unit distance upon each oscillation.

When the projection 99 of the pawl carrying arm 97 falls off the high point of cam 41, the 70 spring 118 suddenly effects movement of the pawl carrying arm and pawl in a clockwise direction, as viewed in Fig. 9, thereby imparting a sudden impulse to the ratchet wheel. When the pawl reaches the limit of its movement in a clockwise 75

direction, the diagonal surface 108 thereof engages the pin 131 of the stop arm and the latter securely wedges the pawl tooth 107 therebetween and a tooth on the ratchet wheel. Thus "overrunning" of the cam shaft is prevented.

The cam shaft may be rotated manually in the same manner as the cam shaft of the previously described modification for the reason that as the cam shaft is rotated the teeth on the ratchet wheel force the pawl 103 upward and the latter, acting through the pin 131 and spring engaging projection 135, lifts the central portion of the spring a sufficient distance so that the pawl tooth 107 rises an amount sufficient to enable the wheel to be turned.

The above specifically described embodiments of the present invention are intended to be illustrative only and not to limit the invention in any manner.

20 I claim:

1. In a drive mechanism for a controller or the like, the combination including a ratchet wheel, a pivotally mounted pawl mounted upon an oscillatable arm, means for oscillating said arm through a predetermined angle whereby predetermined reciprocatory movement is imparted to said pawl, a pivotally mounted dog for preventing reverse movement of said ratchet wheel, a spring connecting the pawl and dog, said spring being mounted on said pawl and dog at points spaced farther from the axis of rotation than a line passing through the pivot points, and pivotally mounted means adapted to engage said pawl and biased toward said pawl by said spring for preventing said wheel from being rotated more than the amplitude of the reciprocatory movement of said pawl upon each oscillation of said arm.

2. In a drive mechanism for a controller or the like, the combination including a ratchet wheel, an oscillatable arm, a pawl pivotally mounted at the free end of said arm and adapted to engage said wheel, a cam for oscillating said arm whereby reciprocating movement is imparted to said pawl, the amplitude of said oscillations being such that the wheel is normally moved a unit distance upon each oscillation, a dog pivotally mounted upon a fixed support, a tension spring connected to said pawl and dog at points farther from the axis of rotation of said wheel than a line passing through the pivot points of said pawl and dog, said spring being adapted to maintain said pawl and dog in engagement with the ratchet wheel and said arm in engagement with the cam oscillating it, and pivotally mounted means having a portion between the spring and ratchet wheel adapted to engage said pawl and biased toward said pawl by said spring for preventing overrunning of said wheel.

3. In a drive mechanism for a controller or the like, the combination including a ratchet wheel, an oscillatable arm, a pawl pivotally mounted at the free end of said arm and adapted to engage said wheel, a cam for oscillating said arm whereby reciprocating movement is imparted to said pawl, the amplitude of said oscillations being such that the ratchet wheel is normally moved a unit distance upon each oscillation, a dog pivotally mounted upon a fixed support, a tension spring connected to said pawl and dog at points farther from the axis of rotation of said wheel than a line passing through the pivot points of said pawl and dog, said spring being adapted to maintain said pawl and

dog in engagement with said ratchet wheel and said arm in engagement with the cam oscillating it, pivotally mounted means having a portion between the spring and ratchet wheel and adapted to engage said pawl and biased toward said pawl by said spring, and means limiting the movement of said pivotally mounted means toward the wheel and thereby the position of the spring.

4. In a drive mechanism for a controller or the like, the combination including a pawl, a spring biasing said pawl and a ratchet wheel driven by said pawl, and means including a pivotally mounted stop arm, a pin extending into the plane of said pawl carried by said arm, and a projection on said arm having a curved portion engaged by said spring for preventing said wheel from overrunning when actuated by said pawl.

5. In a drive mechanism for a controller or the like, the combination including a pawl, a spring biasing said pawl and a ratchet wheel driven by said pawl, and means including a pivotally mounted stop arm having its end in the plane of movement of said pawl and a curved upper portion engaged by the underside of said spring for preventing said wheel from overrunning when actuated by said pawl.

6. In a drive mechanism for a controller or the like, the combination including a support, a ratchet wheel mounted on said support, an arm pivotally mounted on said support, a constant speed cam for oscillating said arm, a pawl pivotally mounted at the free end of said arm and reciprocable thereby for rotating said wheel in a predetermined direction, a dog pivotally mounted on said support for preventing reverse rotation of said wheel, all said pivot points being equidistant from each other and at a distance greater than the radius of the wheel from the axis of rotation of said wheel, a spring connecting said pawl and dog and mounted thereon at points farther from the axis than a line passing through the pivot points of said pawl and dog for maintaining said pawl and dog in engagement with the wheel and said arm in engagement with said cam, other means for rotating said shaft, a stop arm pivotally mounted on said support, having a portion lying between the underside of said spring and the wheel adapted to be engaged by said spring, a pin carried by said support limiting movement of said stop arm toward the wheel, the end of said stop arm extending toward the pawl and being provided with a portion lying in the plane of movement of said pawl, said portion being so constructed and located with respect to the pawl that the pawl is wedged therebetween and the ratchet wheel at the end of each reciprocation thereof by said arm for preventing overrunning of said wheel, said spring having a strength such that it permits movement of said stop arm and pawl when said shaft is rotated by said other means.

7. In a drive mechanism for a controller or the like, the combination of a driven ratchet, a pawl engageable with the ratchet for periodically moving it, means for reciprocating said pawl through a predetermined distance, said means including a spring for moving the pawl through its driving stroke, and a movably mounted stop arm urged in one direction by said spring and engageable with the pawl to prevent the pawl from moving the ratchet more than the distance the pawl is moved.

8. In a drive mechanism for a controller or

- the like, the combination of a driven ratchet, a pawl engageable with the ratchet for periodically moving it, means for reciprocating said pawl through a predetermined distance, said means including a spring for moving the pawl through its driving stroke, manual means to move the ratchet, a movably mounted stop arm urged in one direction by said spring and engageable with the pawl to prevent overrunning of the ratchet, said stop arm moving against the spring to enable the ratchet to be moved by said manual means.

9. In a drive mechanism for a controller or the like, the combination of a driven ratchet, a pivotally mounted pawl engageable with the ratchet for driving it in one direction, a pivotally mounted dog engageable with the ratchet 5 to prevent it from moving in the other direction, a pivotally mounted stop arm engageable with the pawl to prevent the ratchet from overrunning, and a spring engaging the pawl, the dog and the stop arm for biasing all of them in one 10 direction.

CLIFFORD C. BRADBURY.
